UNITED STATES PATENT OFFICE.

JOSEPH A. CARON, OF MONTREAL, CANADA, ASSIGNOR TO CORNELIUS COUGHLIN, OF MONTREAL, CANADA.

DESIGN FOR A BADGE.

SPECIFICATION forming part of Design No. 36,190, dated January 13, 1903.

Application filed October 29, 1902. Serial No. 129,334. Term of patent 7 years.

To all whom it may concern:

Be it known that I, JOSEPH ARTHUR CARON, a subject of His Majesty the King of Great Britain and Ireland, residing in the city of 5 Montreal, in the Province of Quebec, in the Dominion of Canada, have invented and produced a new, original, and ornamental Design for Badges, of which the following is a specification, reference being had to the accompanying drawing, forming part thereof.

The drawing is a plan view of a badge, showing my new design.

As shown in the drawing, my design consists of a cross rising from a crescent-shaped 15 bank of clouds. From the inner angles of the cross are rays which radiate outwardly. In the center of the cross is a heart, with a crown of thorns crossing it horizontally. A small cross surrounded by flames surmounts

the heart. A nude arm extends across the 20 base of the cross to the left, while a clothed arm appears to come from behind the cross and extends from the right. The hands are open and the palms are marked in the center. The whole is arranged as shown.

Having now described my invention, what I claim as new, and desire to secure by Letters Patent, is—

The ornamental design for a badge, as herein shown and described.

In testimony whereof I have signed my name to this specification in the presence of the two subscribing witnesses.

JOS. A. CARON.
